United States Patent Office.

NEAIL N. BROWN, OF PHILADELPHIA, PENNSYLVANIA.

Design No. 2,930, dated February 11, 1868.

DESIGN FOR A GLASS BOTTLE.

The Schedule referred to in these Letters Patent and making part of the same.

TO ALL WHOM IT MAY CONCERN:

Be it known that I, NEAIL N. BROWN, of Philadelphia, Pennsylvania, have originated and designed a new shape for a Glass Bottle, of which the following is a full and exact description.

The shape of this bottle is designed to represent an Indian female figure, one hand resting upon a shield, upon which are inscribed the words "Brown's Celebrated Indian Herb Bitters," the shape being fully represented in the annexed drawings, in which—

Figure 1 represents a front view of the bottle.

Figure 2 is a side view, and

Figure 3 a rear view of the same.

This bottle is chiefly intended to hold preparations from bitter herbs.

What I claim, and desire to secure by Letters Patent, is—

The shape or configuration for a bottle, herein set forth and shown.

NEAIL N. BROWN.
